CONTROL DEVICE

Carl G. Kronmiller, Edina, Minn., assignor to
 Minneapolis-Honeywell Regulator Company,
 Minneapolis, Minn., a corporation of Delaware

Application September 2, 1949, Serial No. 113,884

9 Claims. (Cl. 200—139)

1

This invention is directed to a control point adjusting means applicable to thermostats and other condition controlling devices.

An object of the invention is to provide a control device having adjusting mechanism including a pair of manually positionable cams, one of which adjusts the control point and the other of which positions a pointer with respect to suitable indicia to indicate the selected control point.

Another object is to provide a control device having a knob that may be manually rotated to adjust and indicate the control point and that may be moved axially to actuate a switch controlling a light bulb disposed to illuminate the indicia of condition value.

Other objects will be evident from the following description and claims, and from the drawing, in which

Figure 1 is an elevation of a room thermostat embodying the invention, the cover being removed and certain parts broken away for the sake of clarity.

Figure 2 is a fragmentary section taken on line 2—2 of Figure 4 showing details of the cam adjusting mechanism.

Figure 3 is a fragmentary section taken on line 3—3 of Figure 4 showing details of the connection between the cam structure and the rod that positions it.

Figure 4 is an elevation taken in section along line 4—4 of Figure 1, the cover also being shown in section.

Figure 5 is a rear elevation of the device of Figure 1, and

Figure 6 is a diagrammatic view showing an electrical circuit in which the thermostat may be used.

While the invention is applicable to various control devices, it is illustrated in connection with a thermostat adapted to control the supply of heat to a room. The thermostat has a base 10 of suitable insulating material such as molded Bakelite, the back surface being recessed as at 11 to receive a wall plate (not shown) to which connecting wires may be secured and to which the thermostat itself is secured by its terminal screws in a manner well known in the art. A bracket 12 is secured to the front surface of the base 10 by screws 13 and 14, the screw 13 extending through the base to electrically connect the bracket 12 to a conducting strip 15 shown in Figure 5. The strip 15 carries a terminal screw 16, the slotted head of which is accessible from the front of the base through a hole therein.

The bracket 12 has an outwardly extending portion 12a at its right hand end which carries a

2

spring blade 20. A switch arm 21 is secured to the blade 20 adjacent the bracket portion 12a, the intervening portion of the blade 20 serving as a spring hinge for the switch arm. A movable contact 22 is mounted on the right hand end of the blade 20 and is biased with respect to the switch arm 21 by the blade 20 to provide a limited amount of press back as disclosed in my copending application Serial No. 681,461, filed July 5, 1946, now Patent No. 2,493,294, dated January 3, 1950.

Another bracket 25 is secured to the front surface of the base 10 at the lower right hand corner by screws 26 and 27, the screw 26 extending through the base to form an electrical connection with a conducting strip 28 on the rear surface thereof. A terminal screw 29 is held on the base 10 by the strip 28 and an opening is provided in the base and in bracket 25 to permit access to the screw head. A contact screw 30, the upper end of which is adapted to cooperate with movable contact 22, is adjustably carried in the bracket 25. The bracket 25 also carries a permanent magnet 31 which cooperates with the switch arm 21 to cause snap action of contact 22 into and out of engagement with stationary contacts, the switch arm 21 being made of suitable magnetic material to act as an armature for the magnet 31.

A pivot pin 34 is mounted on the left hand end of bracket 12 and extends outwardly therefrom normal to the base 10. A member 35 having a horizontally disposed bimetal element 36 secured thereto is pivotally mounted on the pin 34, the member 35 having an extension 35a the right hand end of which carries a calibrating screw 38 which engages an adjusting cam to be herein-after described. The right hand end of the bimetal element 36 passes through an opening in a very thin strip 40 which is secured to the extremity of the switch arm 21. As seen in Figure 4 the strip 40 has a very narrow portion intermediate the bimetal 36 and switch arm 21 to render the connection very flexible. This connection between the switch arm and the bimetal element is instrumental in providing a clean snap action of the switch contact since the strip 40 flexes sufficiently during the snap action to prevent sliding action between the strip and the bimetal element.

An anticipating heater 43 is secured to bimetal element 36 by a screw 44 which passes through an insulating washer 45, a conducting washer 46, and is screw threaded into the member 35. Heater 43 is preferably of cylindrical form and is made of a suitable carbon or graphite compo-

sition to provide the desired resistance. A pigtail connection 48 connects the washer 46 with a screw 49 that extends through the base 10 to form an electrical connection with a conducting strip 50 on the back of the base. A terminal screw 51 is carried in the base 10 by the strip 50.

A molded plastic cam shaft 54 has a reduced cylindrical end portion 55 that is journaled in the base 10, as is shown in Figure 4. The outer end of the cam shaft 54 is also provided with a cylindrical bearing portion 56 journaled in a bracket 58, the major portion of which is spaced from the base 10, but which is attached to the base by the screws 60. The cam shaft 54 is provided with shoulders adjacent the reduced portions 55 and 56 to prevent axial displacement thereof. A cam 62, molded integrally with the cam shaft 54, has a spiral working surface that engages the calibrating screw 38 carried by the extension 55a of the bimetal mounting member 35.

A scale plate 64 bearing suitable indicia of temperature thereon is carried by the bracket 58 which also carries a thermometer tube 65 which also cooperates with the indicia on the scale plate 64 to indicate existing temperature. The scale plate 64 is provided with a slot 67 that serves as a guide for a pointer 68 which cooperates with the indicia to indicate the adjusted temperature at which contacts 22-30 will be engaged to call for heat. The pointer 68 is provided with a rearwardly extending pin 70 which is connected by a link 72 to a pin 74 extending parallel to the pin 70 from a lever 76 which is pivoted on a pin 77 in the bracket 58. The link 72 comprises an upper relatively rigid member 72a which is formed at either end to engage pins 70 and 74, and a lower spring strip 72b which holds the pins in engagement with upper portion 72a. This construction permits ready assembly of the pointer 68 on scale plate 64 and also prevents lost motion between the pointer and the lever 76. The lower end of the lever 76 is U-shaped and the rear leg forms a cam follower 80 which is biased by a spring 81 into engagement with a cam 62 that is molded integrally with the cam shaft 54. It will be noted that as the cam shaft 54 is rotated to adjust cam 62, and hence the bimetal elements, to determine the control point of the thermostat, cam 62 is also positioned to adjust lever 76 and hence the pointer 68 to indicate the control point. The bimetal supporting member 35 is biased by a spring 83 in a clockwise direction to assure positive engagement of the calibrating screw 38 with the surface of the cam 62. The action of spring 83 makes it more difficult to adjust the cam 62 in a counterclockwise direction than in a clockwise direction. On the other hand, spring 81 biases the cam follower 80 against the cam 62 (which is oppositely disposed with respect to the cam 62) making it more difficult to adjust the cam 62 in a clockwise direction than in a counterclockwise direction. The combined effect of the springs 83 and 81 on the cam shaft 54 results in there being very little difference in the force required to rotate it in the opposite direction.

Scale plate 64 is formed of a translucent material and is adapted to be illuminated by a light bulb 85 having a conducting base 86 secured in place on the base 10 by a spring strip 87 which grasps the base 86, extends along the base 10 and is secured thereto by a screw 88. The screw 88 extends through the base and forms an electrical connection with a conducting strip 89.

The base 10 and strip 89 are provided with openings through which the head of a terminal screw 90 is accessible. A conducting strip 92 of resilient material is secured to the rear side of the base as seen in Figure 5 by a pair of rivets 93 which also secure a strip of insulating material in overlying relation with respect to the conducting strip 92. An extension 92a of the strip 92 extends outwardly through an opening in base 10 to engage the center terminal connection of the light bulb 85. The lower end 92b of the strip 92 extends through an opening in the insulating strip 94 and overlies its lower extremity. The strip portion 92b is disposed to lie underneath but spaced from an extension 50a of the conducting strip 50 which carries the terminal screw 51.

The strip portion 92b is normally out of engagement with the conducting strip 50 but may be forced into engagement therewith by a pin 96 that extends axially through the base 10, the cam shaft 54, and the bracket 58. The outer end of the pin 96 carries an adjusting knob 98 by means of which the pin 96 can be rotated and moved axially. A spring 99 acting between the outer end of the cam shaft and the knob 98 prevents accidental axial movement of knob 98. It will be seen that the strip 92 and the conducting strip 50 cooperate to form a switch in the light bulb circuit extending from the terminal screw 90 through the strip 87, the light bulb 85 and through the strips 92 and 50 to the terminal screw 51.

As best seen in Figure 3 the pin 96 is laterally bored to receive a pin 100 which has a force fit therein. Pin 100 extends laterally through a slot in the inner end of the cam shaft 54. The pin 100 keys the pin 96 to the cam shaft 54 so that rotational movement of the knob 98 will be imparted to the cam shaft 54 but axial movement of the knob 98 and the pin 96 will be permitted with respect to the cam shaft to actuate the switch 92b-50a.

As seen in Figure 4 a cover 102 is secured to the base 10 and encloses the base and all of the described mechanism with the exception of outer portion of the knob 98 which extends through a suitable opening therein. A transparent window 103 is provided in the cover 102 adjacent the indicia on the scale plate 64, the thermometer tube 65 and the pointer 68.

Under conditions of normal illumination in the room in which the thermostat is installed the knob 98 may be rotated to adjust control point of the instrument and to indicate it on scale plate 64. However, there are many times when it is desirable, as when retiring at night, to adjust the thermostat without turning on general room illumination. Under these conditions the thermostat may be adjusted by pushing in on the knob 98 to energize the light bulb 85 while rotating the knob 98 to select the desired temperature. It is also possible, of course, to employ this light source to merely check the adjusted position of the pointer 68 or to read the thermometer.

One possible electrical circuit in which this thermostat may be employed is shown in Figure 6. A transformer 105 having a low voltage secondary winding 106 may serve as a source of electrical current. The thermostat may be used to control any common load 107 such as a solenoid gas valve, oil burner relay or the like. The main control circuit extends from the trans-

former secondary 106 through a wire 108 to the load 107 and through a wire 109 to the terminal screw 16. Current is conducted through the bracket 12, switch arm 21, contacts 22-30, and the bracket 25 to the terminal screw 29, and thence through a wire 110 to the opposite side of the transformer secondary 106. It will be evident that the load 107 will be energized whenever the thermostat contacts are closed. The left hand connection of the transformer secondary 106 is connected to the terminal screw 51 by a wire 111 which energizes the anticipating heater 43 through the pig-tail 48. The opposite connection to the heater 43 is through the bimetal element and through the member 35 and pin 34 to the bracket 12 which is connected to the opposite side of the transformer secondary whenever the thermostat contacts are closed. Thus heater 43 will be energized whenever the thermostat calls for heat and the heater 43 will supply additional heat to the bimetal element to cause the thermostat contacts to open after an interval of time whether heat is actually supplied to the room or not. When the knob 98 is pushed inwardly the switch 50a-92b will be closed and a circuit will be completed to the light bulb 85 from the terminal screw 51 through conducting strips 50 and 92 to the light bulb 85. Conducting strip 87 connects the base of the light bulb 85 through the terminal screw 90 and a wire 113 to the terminal screw 29.

While the invention has been described in connection with a room thermostat adapted to control a heating system it will be evident to those skilled in the art that it could be equally well applied to a cooling thermostat or for that matter to any other condition controlling device, for example, a room humidostat. Likewise, the invention is applicable to any control device where it is desirable to adjust the control point and indicate it at the same time. Many modifications of the invention will be apparent to those skilled in the art and I am therefore to be limited only by the appended claims.

I claim as my invention:

1. In a thermostat, a base adapted for mounting on the wall of a room, a thermostatic element pivotally mounted on said base, a switch actuated by said thermostatic element, a cam for pivotally positioning said thermostatic element to determine the temperature at which said switch is actuated, a plate carrying indicia of temperature and a pointer movable with respect thereto, a lever pivoted in said base for positioning said pointer with respect to said indicia, a cam for positioning said lever and means for rotating simultaneously both of said cams, said pointer indicating the temperature at which said thermostatic element actuates said switch.

2. In a thermostat, a base adapted for mounting on the wall of a room, a thermostatic element pivotally mounted on said base, a switch actuated by said thermostatic element, a cam for pivotally positioning said thermostatic element to determine the temperature at which said switch is actuated, a plate carrying indicia of temperature rectilinearly disposed thereon and a pointer movable rectilinearly with respect thereto, a lever pivoted in said base for positioning said pointer with respect to said indicia, a link interconnecting said lever and said pointer, a cam for positioning said lever, and means for rotating simultaneously both of said cams, said pointer indicating the temperature at which said thermostatic element actuates said switch.

3. In a control device, a base, a thermostat on said base, a first cam for adjusting the control point of said thermostat, a temperature indicator carried by said base, a second cam for adjusting said indicator, a light bulb for illuminating said indicator, a switch controlling the circuit for said bulb, and manually operable means including a member extending through both of said cams for rotating said cams, said member 10 also being axially slidable in said cams to actuate said switch.

4. In a control device, a base, condition responsive means and control means carried on said base, cam means for relatively positioning said means to adjust the condition value at which said control means is actuated by said condition responsive means, an indicator comprising a pointer and indicia of condition value, a linkage interconnecting said cam means and said 15 indicator for causing said indicator to show the condition value at which said control means will be actuated, a lamp bulb disposed to illuminate said indicia and said pointer, a switch controlling energization of said lamp bulb, and manually 20 positionable means rotatable coaxially with said cam to adjust the control means and slideable axially with respect thereto to actuate said switch.

5. In a control device, a base, a member pivoted in said base, a bimetal element attached to said 30 member, a switch actuated by said bimetal element, an indicator comprising a relatively movable pointer and indicia of temperature, a lever pivoted in said base and a connection between said lever and said indicator, cam means pivoted 35 in said base and engaging said member and said lever, a knob rotatable to adjust simultaneously said bimetal and said indicator, a light bulb disposed for illuminating said indicator, and a switch in control of said light bulb, said switch 40 actuated by axial movement of said knob.

6. In a control device, a base, a member pivoted in said base, a bimetal element attached to said member, a switch actuated by said bimetal element, an indicator comprising a relatively movable pointer and indicia of temperature, a lever pivoted in said base and a connection between said lever and said indicator, cam means pivoted 45 in said base and engaging said member and said lever, manually positionable means including a rod extending axially through said cam means and keyed thereto, a light bulb disposed to illuminate said indicator, and a switch in series 50 circuit with said light bulb, said rod extending through said base to actuate said light switch 55 on axial movement of said manually positionable means with respect to said cam means.

7. In a control device, a base, a thermostatic element and a switch on said base, a bracket on 60 said base having a portion parallel to said base but separated therefrom, a scale plate carried by said bracket, a pointer movable with respect to said scale plate to indicate the temperature at which said element will actuate said switch, 65 a cam pivotally mounted between said base and said bracket portion and confined thereby against axial movement, connections between said cam and said element and between said cam and said pointer, a rod disposed coaxially of said cam 70 and having a knob at its outer end, means interconnecting said rod and said cam causing concurrent pivotal movement thereof but permitting relative axial movement therebetween, a light bulb adapted to illuminate said scale plate and pointer, and a switch in circuit with said light 75

bulb actuated by the inner end of said rod on axial movement thereof.

8. In a thermostat, a base adapted for mounting on the wall of a room, a thermostatic element pivotally mounted on said base, a switch actuated by said thermostatic element, a cam for pivotally positioning said thermostatic element to determine the temperature at which said switch is actuated, a plate carrying indicia of temperature rectilinearly disposed thereon, said plate having a rectilinear slot therein parallel to said indicia, a pointer guided by the slot in said plate and cooperating with said indicia, a lever pivoted in said base for positioning said pointer with respect to said indicia, a link interconnecting said lever and said pointer, a cam for positioning said lever, and means for rotating simultaneously both of said cams, said pointer indicating the temperature at which said thermostatic element actuates said switch.

9. In a control device, a base, a thermostat on said base, a unitary cam structure pivotally mounted on said base and having first and sec-

ond spiral cam surfaces with their effective surfaces rising in opposite directions throughout a predetermined range of angular movement, a cam follower connected to said thermostat engaging said first cam surface, an indicator, a cam follower connected to said indicator engaging said second cam surface, and means biasing each of said cam followers into engagement with said cam surfaces.
